UNITED STATES PATENT OFFICE

REUBEN PURCELL, OF EAST FINCHLEY, LONDON, ENGLAND

PRESS FOR TENNIS AND LIKE RACKETS

Application filed July 11, 1928, Serial No. 291,845, and in Great Britain July 13, 1927.

My invention comprises an improved press for tennis and like rackets of the type in which the head of the racket is clamped in order to prevent distortion whilst not in use.

5 The object of this invention is to provide a simple and compact form of press which may be easily and quickly applied to or removed from the racket and in which the operation of clamping and unclamping the 10 press may be performed by a simple movement. A further object is to enable the press to fold into a small space when not in use.

According to my invention a tennis racket or like press consists of a pair of bodies between which the racket is adapted to be gripped, the invention being characterized in that means for effecting the requisite pressure on the frame of the racket is located approximately opposite the centre of the frame 20 when the press is applied to the frame but does not pass through the stringing of the frame, whereby pressure may be applied to a number of points on the frame from a common point and the press can be slipped over the frame without disassembling its parts.

In a preferred construction of my invention, the two frames may conveniently be of substantially X-shape and each may consist of a pair of transverse members or strips of 25 channel form pivoted together at their centres. From the outer ends of each transverse member or strip a suitable connecting link extends between the two frames. These links may conveniently be metal strips secured at one end to one frame and projecting through an opening or slot in the members of the other frame. Suitable springs or rubber sleeves or other resilient material may be arranged around these links and between the members 30 of the two frames so as to tend to force them apart. These rubber sleeves or springs also act as a protection for the edges of the racket so as to prevent damage when inserting it into or removing it from the frame.

40 The ends of the connecting links, which project through openings in the ends of the members of one frame, are bent over or suitably shaped to permit them to engage over the end of a lever, one of which extends inwardly from each of the ends of the two

frame members. These levers comprise suitable bent metal strips which rest upon the upper face of the frame member at their bent portion whilst the short upwardly bent portion engages over the undeturned end of the 55 connecting links and the long arms of the lever project inwardly toward the centre of the frame. The inner free ends of the levers engage beneath suitable means for forcing them toward the frame of the press. These 60 means may conveniently comprise a screw-threaded nut mounted upon a screw secured in the frame and provided with a knurled edge by which it may be rotated by hand to actuate the levers.

When the knurled nut is unscrewed the rubber sleeves round the connecting links will force the two frames apart causing the levers to turn about their bent portions which act as a fulcrum where they engage upon the frame members. The free end of the levers will thus follow the movement of the screw-threaded nut as it is released. When this nut is released the frames will be separated a sufficient distance to permit the head of a racket 75 to be easily inserted between the two frames or removed therefrom. When a racket has been placed in position between the two frames it may be firmly clamped in position by simply rotating the nut on the screw so as to press the free ends of the levers in towards their frame members. This will draw the two frames together and clamp the head of the racket between them. The only connection between the two frames is their outer 80 ends by means of the connecting links which will be located beyond the edges of the racket. There are no connections passing through the racket thus enabling the racket to be quickly removed directly the pressure 85 between the two frames has been sufficiently released.

90 By arranging the two cross members of each of the frames to be pivotally connected together at their centres, this enables them 95 to be folded into a small space when not in use and also allows them to swivel on each other when placed in position on a racket so that the frame may adapt itself to the shape of the racket head. The frame members may 100

conveniently be made of channel section and may consist of aluminium or other suitable metal stampings. If desired suitable additional stiffening bars may be secured in the channelled members of the frames. These 5 may conveniently consist of short steel or other strips secured at their centres. The connecting links between the two frames may conveniently comprise metal stampings secured to the members of one frame by passing 10 their ends through apertures in the frame members and secured by means of suitable pins or notched keys passed transversely through holes in the ends of the links. This 15 permits of adjustment for different thickness of rackets. Suitable washers may be arranged between these two pins and the frame members.

In order that my invention may be clearly 20 understood and readily carried into effect I have appended hereto a sheet of drawings illustrating an embodiment of same, and wherein:—

Fig. 1 is a plan view showing the press in 25 use.

Fig. 2 is an elevation view of the press.

Fig. 3 is an inverted plan view, and

Fig. 4 is a detail sectional elevation to a 30 larger scale showing one corner of the frame and taken on the line A—B of Fig. 1.

Referring to the drawings the press consists of two frames consisting of a pair of intersecting upper arms 1 and a pair of intersecting lower arms 2. Each pair of arms 35 1 and 2 are connected by pivot pins 1a and 2a respectively, the lower pin 2a preferably being riveted in position and the upper pin 1a being extended above the members 1 in the form of a screw 3 on which is engaged a wing nut 4 the operation of which applies pressure to the outer ends of the intersecting arms for gripping the racket. It will be noticed that the pin 1a does not extend across the members 1 and 2 so that there is no interference 40 to the introduction of a racket into the press without disassembling the press.

The requisite pressure is obtained by a series of levers 5 each engaged at one end under the nut 4, or preferably, under a washer 50 6 located under the nut and free to slide on the screw 3. The fulcrum point of these levers is near to their outer ends, and is approximately at the point 7 (Figs. 2 and 4). The outer ends of the levers are turned up to 55 form toes 8 each engaged under the hook shaped upper end 9 of one of a number of links 10 passed slidably through holes 11 in the outer ends of the arms 1 and 2. The lower end of each link 10 is held against movement 60 relative to the appropriate arm 2 and a coiled spring 12 disposed about each link 10 exerts a separating action on the two sets of arms 1 and 2 and also maintains the inner end of each lever 5 pressed against the base of the 65 washer 6. By this means if the nut 4 is

slackened the springs 12 will increase the space between the said two frames and permit of easy introduction or removal of the racket, but if the nut 4 is tightened it will depress the inner ends of the levers 5 and raise the links 10 with a reduction in the space between the two frames.

In view of the variation in thickness of some tennis racket frames it is desirable to enable the maximum space between the members 1 and 2 to be readily varied, and this can be effected by introducing cotter pins 13 through slots 14 in the lower ends of the links 10, each cotter pin having one or more steps 15 whereby the width of the cotter pin in 70 the slot 14 can be varied.

The members 1 and 2 are preferably formed of channel section metal as shown, each member 1 and 2 having at its centre a flat portion 16 to provide flush engaging surfaces, these 75 surfaces if necessary being fitted with hard wearing metal strips 17 having polished or smooth surfaces, each strip 17 being extended for a short distance along the channel parts of an arm 1 or 2 and formed with a raised 80 portion 18 to increase the strength of the arms at these points and to render them stiffer to withstand bending. The levers 5 can also be of channel section metal.

A press for tennis and like rackets constructed according to my invention may be made in a simple, cheap and compact form. It will effectively maintain the shape of the racket which may be easily placed in or removed from the press by one simple quick 95 movement.

I claim:—

1. A press for tennis rackets comprising two frames each consisting of a pair of rigid bars intersecting each other at about their 105 centres so as to produce two X shaped frames, a pivot pin passed through the intersecting parts of each of the frames so that the ends of the bars of each frame may be moved towards and away from each other, an abutment threaded on one of said pivot pins, links connecting the outer ends of the two frames, abutments on said links, levers lying along the bars of one of the X shaped frames and 110 engaged with said threaded abutment and the abutments of said links.

2. A press for tennis rackets comprising two frames each consisting of a pair of channel section bars intersecting each other at about their centres, flat opposing faces on the bars at their points of intersection, pivot pins through such points of intersection so that the ends of the bars of each frame may be 120 moved towards and away from each other, an abutment threaded on one of said pivot pins, links connecting the outer ends of the two frames, abutments on said links, levers lying along the bars of one of the X shaped frames 125 130

and engaged with said threaded abutment and the abutments of said links.

3. A press for tennis rackets comprising two frames each consisting of a pair of rigid bars intersecting each other at about their centres so as to produce two X shaped frames, a pivot pin passed through the intersecting parts of each of the frames so that the ends of the bars of each frame may be moved towards and away from each other, an abutment threaded on one of said pivot pins, links connecting the outer ends of the two frames, abutments on said links, levers lying along the bars of one of the X shaped frames and engaged with said threaded abutment and the abutments of said links, and coiled compression springs between the outer ends of said frames.

4. A press for tennis rackets comprising two frames each consisting of a pair of rigid bars intersecting each other X fashion at their centres so that two X shaped frames are provided, a screw passing through the centre of one of the frames, a nut on said screw, levers radiating from and engaged under said nut and lying along the said bars of one frame, fulcrum bends near the outer ends of said levers engaging the said frame, links slideable through the outer ends of said frame and connected to the outer ends of the other frame, abutments on said links engaged by the outer ends of said levers, springs tending to separate said frames, and flat engaging faces at the intersecting points of each of said frames.
